CLAIM

I claim the ornamental design for a draw and return tube assembly having a multi-aperture flange, as shown and described.

DESCRIPTION

FIG. 1 is an isometric view of the draw and return tube assembly having a multi-aperture flange looking downwardly toward the front of the assembly;

FIG. 2 is an isometric view of the draw and return tube assembly having a multi-aperture flange looking upwardly toward the rear of the assembly;

FIG. 3 is a bottom plan view of the draw and return tube assembly having a multi-aperture flange;

FIG. 4 is a top plan view of the draw and return tube assembly having a multi-aperture flange;

FIG. 5 is a front elevational view of the draw and return tube assembly having a multi-aperture flange;

FIG. 6 is a rear elevational view of the draw and return tube assembly having a multi-aperture flange;

FIG. 7 is a left side elevational view of the draw and return tube assembly having a multi-aperture flange; and,

FIG. 8 is a right side elevational view of the draw and return tube assembly having a multi-aperture flange.
